SIGNAL DEVICE AND SYSTEM THEREFOR

Howard J. Findley, Cleveland, Ohio, assignor to
The Bishop & Babcock Mfg. Company, Cleve-
land, Ohio, a corporation of Ohio

Application September 14, 1933, Serial No. 689,413

10 Claims. (Cl. 177—7)

This invention relates to signal systems and apparatus and particularly to electrical systems and apparatus adapted to be installed upon a vehicle such for example as an automotive vehicle whereby the driver thereof may effect an audible signal to the driver of another vehicle or to other persons generally.

It is an object of the invention to provide an improved signal system and apparatus of the class referred to 10

Another object is to provide an improved signaling system and apparatus of the class referred to whereby audible signals of a distinctive character may be made.

15 Another object is to provide an improved system and apparatus whereby audible signals may be made having the character of a musical tone or tones.

Another object is to provide an improved signal 20 system and apparatus whereby audible signals may be made having the character of a plurality of harmonious musical tones.

Another object is to provide a musical tone producing signal system and apparatus whereof 25 the musical tones may be selectively changed and/or adjustably varied.

Another object is to provide an audible signal system and apparatus whereby a musical tone or 30 tones may be produced in an improved manner.

35 Another object is to provide an improved signaling system and apparatus for producing a plurality of musical tone signals and having means for sounding the tones at will in any selective sequence whereby to produce audible signals having the character of tunes.

Another object is to provide, for electric signal 40 systems and apparatus of the class or classes referred to hereinabove, an improved electric control circuit or circuits.

45 Another object is to provide, in an improved signaling system and apparatus for producing a plurality of musical tone signals at will, and selectively, an improved controller means for selecting the tones to be produced.

Other objects will be apparent to those skilled in the art to which my invention appertains.

My invention is fully disclosed in the following description taken in connection with the accompanying drawings, in which:

Fig. 1 is an elevational view partly in cross-section of a sound-producing device which I may employ in the practice of my invention;

Fig. 2 is a diagrammatic view of one form of 55 electric circuit which I may employ in connec-

tion with the device of Fig. 1 for electrically energizing the same;

Fig. 3 is a plan view illustrating an apparatus shown diagrammatically in Fig. 2;

Fig. 4 is a diagrammatic view illustrating another electric circuit or system which I may employ in connection with the device of Fig. 1;

Fig. 5 is a side elevational view to an enlarged scale of a controller means illustrated diagrammatically in Fig. 4;

Fig. 6 is a sectional view taken from the plane 6—6 of Fig. 5;

Fig. 7 is an end elevational view of the apparatus of Fig. 3;

Fig. 8 is a diagrammatic view similar to Fig. 2 illustrating a modification;

Fig. 9 is a view similar to a part of Fig. 4 illustrating a modification.

Referring to Fig. 1, I have illustrated at 1, generally, a sound amplifying horn and at 2, generally, an electrically energizable sound-producing device responsive, upon the reception thereby of electric current impulses, to translate the same into sound waves for amplification by the sound amplifying horn 1.

The horn 1 and device 2 may be variously constructed. In the illustrative example thereof of Fig. 1 I have shown at 3 and 4 housing elements having peripheral flanges 5 and 6 clamped together by bolts 7 and clamping therebetween a transversely vibratory diaphragm 8. Suitable annular rings 9—9 may be interposed between the diaphragm and the flanges.

Secured to a central portion of the diaphragm is a tubular winding support 10 having wound thereon an armature winding 11. The winding 11 extends inwardly axially between inwardly radially extending poles 12—12 of an E-form electromagnetic circuit 13, the central pole 14 of which extends axially into the tubular support 10 and therefore into the winding 11. A field winding 15 is provided on the central pole 14 and thus when energized generates magnetism in the gap between the poles 12 and the central pole 14.

In a manner well known in the art, impulses of current directed into the winding 11 will cause it to move axially and vibrate the diaphragm 8 by reaction of the current in the winding 11 upon the magnetic field in which it is disposed as above described. The sound thereby produced by the diaphragm 8 is amplified by the horn 1, the air column in the horn communicating with the air in contact with the diaphragm 8, in a chamber 50

16 provided between the diaphragm and the housing portion 3.

Circuit wires 17 and 18 and circuit wires 19 and 20 are, respectively, led into the housings 5 3—4 to energize the field winding 15 and the armature winding 11 respectively in a manner to be described.

Referring to Fig. 2, I have indicated diagrammatically the diaphragm 8, the field magnet 13, 10 armature winding 11, field winding 15, the field circuit wires 17 and 18 and the armature winding circuit wires 19 and 20.

A source of current such as a storage battery 21 is provided, connected at one terminal to the 15 wire 18 and at the other terminal by a wire 22 to ground.

It is one of the advantages of my invention that it is particularly applicable to motor vehicles; and in such applications, the storage battery 20 of the vehicle may be advantageously employed as the battery 21.

At 23 is indicated a switch of the push button type having a terminal connected by a wire 24 to ground and another terminal connected to the 25 wire 17. The switch 23 may be disposed at any convenient point, such for example as upon or adjacent to the steering wheel 26 of a motor vehicle, and may be of any suitable construction to be conveniently closed and opened by the vehicle driver.

Connected in parallel relation between the wires 17 and 19 is a plurality, such as four, devices 25—25, illustrated diagrammatically for simplicity. Each device comprises an electro-magnet or a pair of electromagnets 26—26, a vibratory reed element 27 rigidly supported at one end as at 28 and carrying on its free or vibrating portion an armature 29 disposed to be attracted by the electromagnets 26—26. On the free end 30 portion of the reed 27 is a contact 30 movable therewith engageable with the stationary contact 31 preferably supported on the end of a screw 32 adjustably threaded in a stationary support 33. The electromagnets 26 are connected in series with the contacts 30—31 across the wires 17 and 19, the reed 27 forming part of the circuit.

By this arrangement, current flowing in the windings of the electromagnets 26 will attract 50 the armature 29 and break the circuit at 30—31 whereupon the reed will retract and again close the circuit. The reed therefore will vibrate back and forth interrupting the current in the wires 17—19, causing current impulses to flow therein. The reed 27 may have a normal periodicity 55 of vibration and this may be adjustably changed through a limited range by a screw 34 threaded through a stationary support 35 and abutting at an end portion 36 upon the reed 27, as shown 60 for the reed 27.

Each of the devices 25 may be of the construction just described and preferably the reeds 27, 27A, 27B, 27C of the four devices are of different 65 lengths to provide different vibratory periodicity for each reed.

As will now be apparent from the foregoing description, upon closing the switch 23, current may flow from the battery 21 through the field 70 winding 15 over the wire 17 and through the switch 23 to ground, thus completing the circuit and energizing the field of the sound-producing device 2. Current may also flow from the battery 21 through the wire 20 energizing the armature winding 11, and this current flows through 75

the wire 19 and through each of the devices 25, that is to say, through the contacts and windings thereof to the wire 17, and thence through the switch 23 to ground.

The devices 25 operate automatically as above 5 described to interrupt the current in the circuit of the armature 11 and by choosing reeds 27 of the vibrating frequency of musical tone, the armature winding 11 will be energized with impulses of musical tone frequency and, as will 10 now be clear, will cause a musical tone to be emitted by the sound amplifying horn 1.

My invention contemplates the employment of a single device 25, and in such case it will be clear 15 that the tone emitted by the horn will be a more or less simple or single musical tone of any desired pitch determined by the periodicity of the reed 27. It is preferred, however, that a plurality of devices 25 be employed and in such case 20 the reeds 27 are selected to have vibratory periodicity corresponding to the tones or notes of a musical chord, and thus the impulses energizing the armature winding 11 will be current impulses composed of a plurality such as four impulses of different frequency; that is to say, the current impulses will be composite impulses and the tone emitted by the horn 1 will be a tone of beautiful quality and harmonious effect.

In the form of my invention just described, 30 upon each closure of the switch 23, the harmonious musical tone will be emitted from the horn 1.

The form of impulse-producing device, 35 25, above described is intended to be diagrammatic in order that it may conveniently be represented in the diagram. In practice I prefer to employ a device more generally like that illustrated in Figs. 3 and 7, wherein I have used reference characters so far as practicable the same as those of the devices 25 of Fig. 2. A main supporting frame 60 40 which preferably may be made of non-metallic material has mounted therein a plurality such as four magnet cores of E-form 61 on the central pole of which is a winding 26. The frame has opposite spaced pairs of supports 62 and 63 to 45 which are rigidly secured the opposite ends of vibratory reeds, 27, 27A, 27B, 27C. These reeds are of successively short length and greater width and greater thickness as plainly illustrated in Fig. 3, whereby they may have successively higher 50 natural periods of vibration. The ends of each reed are secured to the supports 62 and 63 by screws 64 and 65 and under the head of the screw 64 may be provided an adjusting element 66 in the form of an elongated washer having an elongated slot therein, an end portion of the washer overlapping an adjacent portion of the reed. By varying the amount of the overlap, the periodicity 55 of the reed may be slightly adjustably varied. If preferred, also, a weight element 67 may be provided on the reed and constructed to permit its position to be adjustably changed longitudinally 60 of the reed also for tuning purposes.

A contact 30 is provided on a middle portion 65 of the reed and a stationary contact 31 is provided upon an adjusting screw 32 in a stationary support 33 secured to the frame 60. The support 33 may be metallic and have a terminal connection 68 thereon. A wire 69 may lead from the circuit wire 17 to the winding 26 and the wire 70 70 may lead therefrom to a ground on the reed 27.

The mode of operation will be apparent from the more complete description of the diagrammatic form of Fig. 2. Current flowing in at the wire 19 and through the contacts 30—31 and by 75

way of the reed to the wire 70 and through the winding 26 to wire 69 to the wire 17, will energize the winding 26 and separate the contacts 30-31 whereupon the reed 27 will retract and again close the contacts resulting in a rapid vibration of the reed and the production of current impulses. By means of the devices 66 and/or 67, the periodicity or tone of the reed may be adjusted to musical pitch; and, by the tuning means mentioned, the four reeds may be adjusted if desired to the frequency of four tones of a musical chord.

In Fig. 2, at 71 and 72 respectively, I have illustrated a condenser and a resistance bridged across the contacts 30-31. By suitably providing capacitance and resistance in these devices, the sparking at the contacts 30-31 may be reduced to the minimum. Such devices also, as will be obvious, may be used in connection with the vibrating device of Figs. 3 and 7.

In the form of my invention illustrated in Figs. 4 and 5, means is provided to produce any one of a plurality of musical tones by the horn 1 selectively, or any number of them from one to eight of different pitch and in unison, or to sound them individually or in combination in any desired succession or sequence to play tunes thereby.

The wire 17 goes to a switch, such for example as a push button type of switch 40, and through that switch to a wire 41 connected to the ground and by a plurality such as eight connecting wires 42 to a corresponding plurality of push button switches 43 from each of which is an outgoing wire 44. Each of the wires 44 is connected to the electromagnet or electromagnets 26 of a device 25 such as that above described, having contacts 30 and 31. The stationary contacts 31 are all connected to a wire 45 which in turn is connected to the wire 19.

The devices 25 are each provided with vibratory reeds 27 and 27a to 27g, and preferably these eight vibrating reeds are constructed and adjusted to vibrate with periodicities varying from each other by intervals corresponding to the intervals between adjacent notes or tones of one octave of a musical scale.

In Fig. 5 is illustrated one form of a unitary controller or switch device 47 which I may employ embodying the push button switches 40 and 43-43. It comprises a base 48 and a plurality such as eight push buttons 43 which may be disposed in a circular arc as illustrated in the plan diagrammatic view of Fig. 4; and comprises also a push button device 40 which may conveniently be located at the center of the circular arc of the push buttons 43. The button 44 is also conveniently spaced from the buttons 43 so that it may be depressed by the palm or the heel of the hand of an operator and while so depressed the thumb and fingers of the operator's hand will lie conveniently over the buttons 43 whereby they may be pressed selectively, singly or in combination in the nature of a musical instrument key board.

In the operation of the system and apparatus illustrated in Figs. 4 and 5, the operator first closes the push button switch 40, as for example by the heel or palm of his hand as illustrated in Fig. 5. Current may then flow from the battery 21, the field winding 15 and by wire 17 and push button switch 40 and wire 41 to ground, energizing the field of the sound-producing device 2. Thereafter, upon pressing any one or any plurality of the push buttons 43, current will flow from the battery 21 through the armature wind-

ing 11 and by wires 19 and 45 will flow through the contacts 30-31 of a device or devices 25 through their energizing windings 26 and through the corresponding push button switch 43 and by wires 42 and 41 to ground. The corresponding device or devices 25 will thereby be energized and each will effect the production of current impulses in the armature winding 11, and as was described in connection with the form of Figs. 1 to 3, will cause musical sound to be emitted from the horn 1.

The degree of energization of the field winding 15 thus remains constant whether one or more of the devices 25 are energized. Furthermore, by a natural and convenient movement of the operator's hand, the field may first be energized and then the current impulses transmitted to the armature winding 11.

If desired, in operating the device of Fig. 5, the push button switches 43 of a selected chord may first be depressed and then by pressing the button 40 this chord may be sounded on the horn.

Obviously, tunes may be played on the buttons 43-43, and for this reason it may be desirable to employ, as above referred to, eight devices 25 each corresponding to a note of an octave of a musical scale.

The details of the controller of Fig. 5 may be variously modified. In that figure one form of contacting arrangement is illustrated. The push button 43 has a stem 50 slidable axially in a bore 51 formed in a boss 52 on the inner wall of the housing 73 of the controller. A spring 53 supports the button 43 in its retracted position, a screw 54 securing the spring to the housing 73 and serving as a connection point for the wire 42 of Fig. 4. A terminal element 55 is secured by a screw 56 to the housing and the screw serving also as a terminal connection for the wire 44 of Fig. 4. On depressing the button 43 the end of the spring 53 contacts the element 55 to close the circuit above described.

If desired, a laterally extending pin 56' may be provided on the stem 50 of the button slidable in a groove 57 in the boss 52. By depressing the button sufficiently, the pin 56 may be rotated with the button to the position 58 of Fig. 6 where it underlies the inner surface of the boss 52 to hold the button in its depressed or contact engaged position.

This feature may be employed where it is desirable to be able to sound the horn merely by depressing the button 40. Any one or a combination of the buttons 43 thus may be depressed and rotated to selectively predetermine the sound to be produced by the horn, and thereafter that signal may instantly be produced by merely pressing the button 40. In this aspect the result and general mode of operation will be the same as that for the form of Figs. 1 to 3, but has the advantage that the sound of the horn may be widely varied by the selection of buttons 43 to be fixed in the closed circuit position; and has the further advantage that the device of Figs. 5 and 6 may be operated as a keyboard instrument when the buttons 43 have all been released and allowed to take up their open circuit position.

In order that current may not flow through the armature winding 11 pending depression of the switch 40, when push buttons 43 are held in their closed position, a relay 75 may be provided normally opening the line 19 and adapted to be closed by an electromagnetic device 76 energized by wires 77 and 78 upon closure of the switch 40.

As an alternative mode of effecting this func-

tion, the arrangement of Fig. 9 may be employed. The core 79 of the sound-producing device may have a magnetic resilient flux shunting element 80 rigidly secured at one end to an extension 81 on the core 79 and disposed adjacent another projection 82 spaced therefrom. Upon energizing the winding 15, magnetic flux will flow through the element 80 and cause it to be attracted to the projection 82 and this movement 10 may be utilized to close the circuit of the armature winding 11 by connecting one end of the element 80 to the line 18 by a wire 83, and providing a contact 84 on the element 80 engageable when so attracted with a contact 85 to which is 15 connected the line 20.

In the modification of my invention illustrated in Fig. 8, I have illustrated a system generally similar to that of Fig. 2. In this form, however, a different type of vibratory contact device is 20 indicated. A permanent magnet 90 is employed for each vibrator having a central pole 91 and lateral poles 92—92. A winding 93 is secured to a vibratory diaphragm or reed device 94 and surrounds the end portion of the pole 91 between the 25 poles 92. A contact 95 on a central portion of the diaphragm 94 normally engages a stationary contact 96 on an adjusting screw 97. Current in the line 19 may flow by a wire 98 through the winding 93 to the diaphragm or reed 94, thence 30 through the contact 95 to the contact 96 and screw 97, from which a wire 99 leads to a wire 100 and thence to ground through the switch device 23 as in the form of Fig. 2.

The winding 93 is thereby caused to move to 35 draw the reed 94 in the direction to separate the contacts 95—96 and break the energizing circuit in the winding 93, thus setting up a rapid vibration and causing impulses of current to flow. Otherwise the operation of the form of Fig. 3 40 is the same as that of Fig. 2. The device just described may be indicated generally by the reference character 102 and a plurality, such as four, of such devices 102 may be provided as indicated in Fig. 8. Thus the impulse energizing the armature winding 11 may be a composite of four harmonic 45 impulses.

Whereas in the foregoing specification and in the appended claims I have referred to the apparatus as producing musical tone frequency and to the sound producing device as emitting musical tones, it is not to be inferred that my invention 50 is limited to the production of signal tones having the aesthetic quality usually associated with the word "musical"; and such expressions as 55 "musical tone" in the appended claims are to be taken as meaning any defined tone of definite frequency which can be audibly produced as a signal.

My invention is not limited to the exact details 60 of construction shown and described. Many changes and modifications may be made within the scope and spirit of my invention without sacrificing its advantages.

I claim:

65 1. In an electric signaling system and apparatus, an electrically actuatable sound-producing means responsive to undulatory electric current of musical tone frequency to produce a musical tone and comprising an electrically energizable magnetic field producing element and an electrically energizable armature element, a source of electric current, an armature circuit and a separate field circuit including the current source, current controller means comprising an 70 electrically actuatable device for producing an 75 electrically actuatable

undulatory current in said armature circuit of a predetermined frequency, an electrically actuatable switch controlling the armature circuit, a single operable means for controlling the energization of the field circuit and actuation of 5 said switch.

2. In an electric signaling system and apparatus, an electrically actuatable sound-producing means responsive to undulatory electric current of musical tone frequency to produce a musical tone and comprising an electrically energizable magnetic field producing element and an electrically energizable armature element, a source of electric current, a normally open armature circuit and a separate normally open field circuit including the current source, current controller means for producing undulatory current in the armature circuit of said frequency comprising a plurality of electrically actuatable vibratory contact devices each having a different predetermined frequency of vibration, a plurality of selectively operable switches for controlling the actuation of the vibratory contact devices selectively and a single operable switch for effecting closing of the field circuit concurrently with 10 operation of one or more of the selectively operable switches.

3. In an electric signaling system and apparatus, an electrically actuatable sound-producing means responsive to undulatory electric current of musical tone frequency to produce a musical tone and comprising an electrically energizable magnetic field producing element and an electrically energizable armature element, a source of electric current, an armature circuit and a separate field circuit including the current source, current controller means comprising a plurality of electrically energizable vibratory contact devices in the armature circuit and a plurality of switch means for selectively energizing the devices for selectively producing undulating currents in the armature circuit of different musical tone-producing frequencies to selectively effect the production of different musical tones, an electrically operable switch 30 controlling the armature circuit, and operable switch means for controlling energization of the field circuit and said switch independently of the armature circuit.

4. In an electric signaling system and apparatus, an electrically actuatable sound-producing means responsive to undulatory electric current of musical tone frequency to produce a musical tone and comprising an electrically energizable magnetic field producing element and an electrically energizable armature element, a source of electric current, an armature circuit and a separate field circuit including the current source, current controller means comprising a plurality of electrically energizable vibratory contact devices in the armature circuit for selectively producing undulating currents in the armature circuit of different musical tone-producing frequencies to selectively effect the production of different musical tones, and a plurality 40 of operable switch means provided with operable means for optionally retaining them in operated condition for selectively energizing when operated the electrically energizable devices, an electrically actuatable switch controlling the armature 45 circuit and a single separate operable switch means for effecting operation of the electrically actuatable switch and energization of the field circuit, independently of energization of the armature circuit.

5. In an electric signaling system and apparatus, an electrically actuatable sound-producing means responsive to undulatory electric current of musical tone frequency to produce a musical tone, and comprising an electrically energizable magnetic field producing element and an electrically energizable armature element, a source of electric current, an armature circuit and a separate field circuit including the current source, controller means comprising an electrically actuatable vibratory contact device having a predetermined fixed periodicity for producing undulatory current in the said armature circuit of said frequency, an electrically actuatable switch controlling the armature circuit, operable means for controlling the actuation of the controller means and separate operable means for controlling the energization of the field circuit and said switch independently of energization of the armature circuit. 10
6. In an electric signaling system and apparatus, an electrically actuatable sound-producing means responsive to undulatory electric current of musical tone frequency to produce a musical tone, a field circuit for the sound-producing means, an energizing circuit for the sound-producing means, an electrically actuatable device for producing in the energizing circuit undulating electric currents of musical tone frequency, an electro-magnetic switch controlling the energizing circuit, and a master switch controlling both the field circuit and operation of the electro-magnetic switch. 15
7. In an electric signaling system and apparatus, an electrically actuatable sound producing means responsive to undulatory electric current of predetermined frequency to produce tone, and comprising an electrically energizable magnetic field producing element and an electrically energizable armature element, a source of electric current, an armature circuit and a separate field circuit including the current source, controller means for producing undulatory current in the said armature circuit of said frequency, an electrically actuatable switch controlling the armature circuit, operable means for controlling the actu- 20
- ation of the controller means, and separate operable means for controlling the energization of the field circuit and said switch independently of energization of the armature circuit. 25
8. In an electric signaling system, an electric circuit comprising in series relation a source of current, a master switch, and three parallel circuit branches, an electrically actuatable sound-producing means comprising an undulatory current responsive armature in one branch and comprising a field in another branch and a switch having a winding in the third branch the switch having contacts controlling the said armature branch, a plurality of devices and a corresponding plurality of conductors connected to the armature branch for producing in said branch and in the armature selectively a plurality of undulatory electric currents of sound-producing frequency, selective switches controlling the conductors respectively, to cause the sound producing means, to produce sound under joint control of said master switch and selective switches. 30
9. A signaling system as described in claim 8 and in which the undulatory electric current producing devices are electrically actuatable by current in the said armature branch. 35
10. In an electric signaling system, an electric circuit comprising in series relation a source of current, a master switch, and a pair of parallel circuit branches, an electrically actuatable sound producing means comprising an undulatory current responsive armature in one branch and comprising a field in another branch, a switch having contacts controlling the said armature branch and electro-magnetically operable by the said field, a plurality of devices and a corresponding plurality of conductors connected to the armature branch for producing in said branch and in the armature selectively a plurality of undulatory electric currents of sound producing frequency, selective switches controlling the conductors respectively, to cause said sound producing means, to produce sound under joint control of said master switch and said selective switches. 40

HOWARD J. FINDLEY.
